UNITED STATES PATENT OFFICE

152,200

DESIGN FOR AN ADJUSTABLE LOUNGE
CHAIR

Frank J. Luketa, Seattle, Wash.

Application July 14, 1947, Serial No. 140,265

Term of patent 14 years

(Cl. D15—1)

To all whom it may concern:

Be it known that I, Frank J. Luketa, a citizen of the United States of America, residing at Seattle, in the county of King and State of Washington, have invented a new, original, and ornamental Design for an Adjustable Lounge Chair, of which the following is a specification, reference being had to the accompanying drawing, forming part thereof.

Figure 1 is a perspective view, showing the adjustable lounge chair in normal seating position, with the headrest and footrest retracted and the table surface in supporting position.

Figure 2 is a perspective view, showing the adjustable lounge chair in reclining position, with the headrest and footrest each projected, and with the table in open or supporting position.

Figure 3 is a plan view of the adjustable lounge chair, the position of the parts being generally similar to their position in Figure 1, except that the table is in nonsupporting or folded position

while Figure 4 is a side elevational view of the same, with parts in the same general position as in Figure 3.

Figure 5 is a rear view of the adjustable lounge chair, the table being in folded or closed position.

I claim:

The ornamental design for an adjustable lounge chair, substantially as shown.

FRANK J. LUKETA.
